RADIO TIME SWITCH

David A. Bruton, Albemarle, N. C.

Application February 2, 1945, Serial No. 575,828

2 Claims. (Cl. 200—38)

1

This invention relates to time switches for energizing electrical equipment, and more particularly, to a time switch adapted to energize a radio receiver at predetermined time periods.

A main object of this invention is to provide an improved structure for automatically turning on a radio receiver at predetermined times in order that desired scheduled radio programs may be heard.

A further object of this invention is to provide for automatic radio time switch for turning on a radio receiver at scheduled times and for maintaining the receiver energized for the duration of the desired programs, automatically de-energizing the receiver at the scheduled time of conclusion of said programs.

Further objects of this invention will appear from the following description and claims, and from the accompanying drawings, wherein—

Figure 1 is a view in end elevation of a time switch in accordance with this invention.

Figure 2 is a plan view of the time switch of Figure 1.

Figure 3 is a view in side elevation of the time switch of Figure 1.

Figure 4 is a vertical cross-sectional view taken through the drum member of the time switch of Figure 1.

Figure 5 is a cross-sectional view taken on line 5—5 of Figure 4.

Figure 6 is a perspective view of a rockable lever member employed in the time switch of Figure 1.

Many of the regularly scheduled radio programs now being broadcast are interspersed with material undesired from the listeners' standpoint, and many listeners do not care to hear this undesired material while waiting for a favorite program to be presented. However, unless close attention is paid to the time, the receiver may not be turned on to provide the desired program, especially if the listener becomes preoccupied with other activities during the period preceding the desired program. It is, therefore, a prime purpose of this invention to provide automatic energization of the receiver at the proper time for the scheduled program without requiring the continuous attention of the listener. Referring to the drawings, 1 designates a conventional clock mechanism, the case of which is secured by a bracket 2 to an arm 3 forming part of a hollow front end frame element 4 of a supporting structure which carries the control mechanism of the switch device of this invention.

The supporting structure comprises a flat rectangular base 5 having upwardly projecting

therefrom the hollow front end frame element 4 and a first rear end element 6 secured to base 5 by a screw 7. Frame element 4 is perpendicular to base 5 at the lower portion thereof and is aligned with end element 6. A horizontal shaft 8 is journaled between the top portion of element 6 and the top portion of the vertical part of element 4. The upper portion of element 4 comprises parallel inclined arms 3 and 9 which merge at their top portions into a horizontal top wall 10. Top wall 10 is integrally united to base 5 by a vertical side wall 11.

A second rear end frame element 12 extends upwardly from base 5 to top wall 10, being rigidly secured to said base and top wall, and is further provided with a transverse horizontal top portion 13 and a downwardly projecting front portion 14 rigidly secured to top wall 10. Secured between front portion 14 and rear portion 12 is a horizontal shaft 15.

Integrally formed in side wall 11 is a switch housing 16 provided with appropriate switch means adapted to be closed by downward movement of an actuating plunger 17 which is biased to an upper position by a coiled spring 18. When plunger 17 is depressed, contact is made inside housing 16 to electrically connect wire leads 19 and 20 and to close the energizing circuit for the radio receiver.

30 The shaft for the hour hand of clock 1 extends rearwardly through the clock casing and is journaled in arms 3 and 9, said shaft being provided with a gear 21. Gear 21 meshes with an idler gear 22 mounted on a second shaft 35 journaled in arms 3 and 9, which in turn meshes with a gear 23 mounted on shaft 8. Shaft 8 carries a drum member 24 rigidly mounted thereon inwardly of the frame structure. Drum member 24 is provided with horizontal hour markings, which, with reference to a fixed pointer 25 denote the time. The values of time indicated by pointer 25 are set by properly adjusting drum 24 on shaft 8, so that they will correspond with the values indicated by the hour hand of clock 1.

45 Drum member 24 is provided with a double row of peripheral slots 25, so arranged that the slots overlap completely around the periphery of the drum. Said slots 25 are adapted to receive the shank portions 29 of cam members 27, said cam members being shouldered at their outer portions to bear on the outer surface of the drum member 24 while being secured from inside said drum member by wing nuts 28 threadedly engaged with the shank portions 29 and bearing against washer members 30 provided between

wing nuts 28 and the adjacent inner surface of drum member 24.

Cam members 27 are formed with inclined portions 31 and curved top portions 32. Pivotedly mounted on shaft 15 is a lever member 33 having a cam contacting arm 34 and a plunger contacting arm 35. Lever member 33 is of substantial width and intersects the vertical planes of both rows of slots 26. Said lever member 33 is biased by spring 18 to a position wherein the lower straight edge of cam contacting arm 34 is normally maintained closely adjacent to the surface of drum member 24, a stop member 36 being formed on the lever member 33 which cooperates with horizontal arm 13 to limit the biasing action so that said lower straight edge of arm 34 will not normally actually touch the drum surface. However, as drum member 24 rotates, responsive to the action of clock 1 which is transmitted to shaft 8 by gears 21, 22 and 23, the cam members 27, positioned at predetermined positions corresponding to time values in appropriate slots 26 in the drum member 24, contact arm 34 and rock lever member 33, thereby causing arm 35 to depress plunger 17 and establish electrical contact between wires 19 and 20. This contact will be maintained until the lower contacting edge of arm 34 rides off the cam member 27, whereupon spring 18 causes plunger 17 to rise and open the switch. Thus the duration of contact will depend upon the length of the top flat portions 32 of the cam members 27, since the switch contacts will be closed only while contact arm 34 bears on said flat portions. Therefore in order to provide energization of the receiver for programs of various lengths, cam members 27 are provided having flat top portions 32 of corresponding lengths. The position of said flat top portion with respect to the calibration marks on drum member 24 will indicate the time and duration of energization of the receiver which will be produced by a given cam member 27 in a particular position of adjustment in its slot 26.

In operating the device, clock 1 is set to the correct time and the various cam members 27 are selected and adjusted on drum member 24 in accordance with the scheduled programs desired to be heard. Wire lead 19 is connected to one terminal of the receiver power switch and wire lead 20 is connected to the other terminal of said power switch, the power switch being left in the "off" position. In this manner the time switch of this invention is substituted for the conventional radio receiver switch, but the conventional switch may be used to energize the receiver at any desired time independently of the time switch.

With the power switch open, the clock and gearing will rotate drum member 24, causing energization of the receiver as contact arm 34 rides up onto the flat top portion of each cam member and deenergizing the receiver as soon as said contact arm rides off said top portion. In this manner the receiver is energized in accordance with the predetermined desired schedule.

While a specific embodiment of a time switch for radio receivers and other electrical devices has been disclosed in the foregoing description, it will be understood that various modifications within the spirit of the invention will occur to

those skilled in the art. Therefore, it is intended that no limitations be placed on the invention other than as defined by the scope of the appended claims.

5 What is claimed is:

1. A time switch, comprising a support, a rotatable drum mounted upon the support and including a periphery and a closed end and having one end open, said periphery being graduated circumferentially in units of time, said periphery having circumferentially extending elongated slots co-related with the graduations, lugs mounted upon the outer face of the periphery and wider than the slots to form shoulders engaging the periphery, inwardly extending radial shanks carried by the lugs and projecting through the slots to the interior of the drum, washer members arranged within the drum and mounted upon the shanks, winged nuts within the drum having screw threaded engagement with the shanks and engaging the washer members, a switch biased open and mounted upon the support and arranged near the drum, a pivoted lever to operate the switch and arranged to contact with the lugs and be shifted thereby, and means to turn the drum.

2. A time switch, comprising a support, a rotatable drum mounted upon the support and including a periphery and closed end and having an open end, said periphery being graduated circumferentially in units of time, said periphery being provided with a plurality of sets of circumferentially extending slots, the slots in one set being staggered with the slots in the other set and overlapping therewith, the graduations being common to both sets of slots, a set of lugs for each set of slots, the lugs in each set being mounted upon the outer face of the periphery and wider than the slots to form shoulders engaging the periphery, inwardly extending radial shanks carried by the lugs and projecting through the slots to the interior of the drum, washer members arranged within the drum and mounted upon the shanks, winged nuts within the drum having screw threaded engagement with the shanks and engaging the washer members, a switch biased open arranged near the drum and mounted upon the support, a pivoted lever to operate the switch and having a wide end to span both sets of lugs to be engaged by both sets and moved thereby, the arrangement being such that access may be had to the thumb nuts through the open side of the drum.
